Primary Examiner — Daniel Bui(74) *Attorney, Agent, or Firm* — Beck & Tysver PLLC**CLAIM**

(57) The ornamental design for a mobile vehicle power adapter, as shown and described.

DESCRIPTION

FIG. 1 is a top, left and back perspective view of a mobile vehicle power adapter showing our new design;

FIG. 2 is a right side view thereof.

FIG. 3 is a left side view thereof.

FIG. 4 is a top view thereof.

FIG. 5 is a bottom view thereof.

FIG. 6 is a back view thereof; and,

FIG. 7 is a front view thereof.

The broken line portion of the figure drawings is included for the purpose of illustrating environment and forms no part of the claimed design.
